LOCKING SLIDER FOR SLIDE FASTENERS

John B. Griffin, Oakville, and Albert W. Hagan,
 Stratford, Conn., assignors to United States
 Rubber Company, New York, N. Y., a corpora-
 tion of New Jersey

Application July 26, 1945, Serial No. 607,240

5 Claims. (Cl. 24—205.14)

1

This invention relates to separable slide fasteners and more particularly to locking means for preventing accidental movement of the slider along its stringer.

Many different forms of locking means for slide fasteners have been proposed heretofore and the present invention relates to the type of locking means that moves automatically to the locking position when not held by the pull tab in the unlocked position.

One important feature of the present invention resides in a slide fastener comprising a stringer having a slider adapted to be moved back and forth along the stringer by a pull tab, and also having a locking arm pivotally mounted on the slider and adapted to be moved to its unlocked position by the pull tab which exerts a camming action on the arm to unlock it.

Another feature of the present invention resides in the construction whereby when the pull tab is actuated to move the slider in either the slide fastener opening or closing position, it will exert a camming action on the locking arm to move it to the unlocked position.

Another feature of the present invention resides in a slide fastener, the slider of which is provided with a pivotally mounted locking arm and this arm has a locking tongue adapted to enter the space between two separate rows of fastener elements, and is specially constructed so that it will engage the end of an element of one row and will enter partly between two elements of the opposite row to thereby hold the slider from moving in either direction along its stringer.

The above and other features of the present invention will be more fully understood from the following description when read in connection with the accompanying drawings, wherein:

Fig. 1 is a top plan view of a slide fastener constructed in accordance with the present invention.

Fig. 2 is an enlarged side view of the slider of Fig. 1, the fastener tapes being omitted.

Fig. 3 is an enlarged sectional view of the slider taken on the line 3—3 of Fig. 1.

Fig. 4 is a sectional plan view of the slide fastener, the section being taken on the line 4—4 of Fig. 2, and additionally showing the fastener tapes.

Fig. 5 is a perspective view of a modified type of locking arm which may be employed in accordance with the present invention; and

Fig. 6 is a top plan view on the scale of Fig. 1 of a slider constructed to receive the modified locking arm of Fig. 5.

2

The separable slide fastener shown in Fig. 1 of the drawing comprises a pair of fastener tapes 10 and 11 having the interlocking elements 12. These fastener tapes together form what is known as a stringer and upon which is mounted the slider 13 adapted when moved in one direction along the stringer to interlock the elements 12 and when moved in the opposite direction along the stringer to unlock the elements, in a well known manner. For convenience in describing the device, the movement of the slider 13 in the direction to unlock the elements is referred to as the rearward direction and the movement of the slider in the opposite direction is referred to as the forward direction. The narrow and the broad ends of the slider 13 are likewise designated as the rear and forward ends, respectively. These parts designated by reference characters 10 to 13 inclusive may be of usual construction, except for the locking features.

The slider 13 has a bottom wing 14 and top wing 15 which are integrally connected by the frog 16 that retains these wings in spaced relation to each other so that the tapes 10 and 11 may travel in the clearance space provided between the upwardly extending flanges 17 on the bottom wing and downwardly extending flanges 18 on the top wing.

The top wing 15 has upon its upper surface a pair of spaced integral ribs 19 and between these ribs is provided a channel 19' adapted to receive the locking arm 20 that is pivotally secured therein by the pivot pin 21 so that the arm 20 may rock from its locking position in which it is shown in full lines in Figs. 2 and 3 to the unlocked position in which it is shown in dotted line in Fig. 3. The use of the word "integral" herein is in the sense that the parts of the slider body comprising the bottom and top wings 14 and 15, frog 16, and spaced ribs 19 are made in one piece from a single piece of material.

The locking arm 20 is continuously urged towards its locking position by a coiled or flat spring. A coiled spring 22 is shown as confined in 45 a slot formed in the frog 16 and adapted to press against the downwardly extending portion 23 of the locking arm to urge this arm into locking position. The arm 20 as shown in Figs. 2, 3 and 4 has a downwardly extending locking tongue 24 adapted to lie between the separated rows of elements 12 in a manner to be hereinafter more fully described.

In the modified construction shown in Figs. 5 and 6 the locking tongue 24 has been omitted and 55 in place thereof the locking arm 25 may be pro-

3

vided at one end with the offset downwardly extending locking projection 26 adapted to enter between a pair of elements upon one tape. In order to accommodate this offset locking projection 26 the slider 27 is shown in Fig. 6 as provided with the clearance slot 28 for the projection 26.

The element engaging tongue 24 is preferably constructed as shown in section in Fig. 4, wherein it will be seen that one side wall 24a of this tongue extends in a direction substantially parallel with the axis of the slider, that is in the direction of movement of the slider along the stringers, and the opposite side wall 24b of the tongue converges rearwardly towards the first wall in the direction of the engaged fastener elements 12. The purpose of this is to cause such inclined side wall to abut against an end of an element 12 of the tape 11 as shown in Fig. 4 and thereby prevent the slider from moving in the fastener opening, or rearward direction along the stringer, while the opposite or horizontal side wall will protrude to some extent between two adjacent elements of the tape 10 to block movement of the slider in the opposite direction along the stringer. In order that this horizontal portion of the tongue 24 may enter between two elements as shown in Fig. 4 it may be necessary to point the end of the tongue somewhat, to thereby facilitate its introduction into the space between two elements as the locking arm 20 moves to its locking position under the influence of the coiled spring 22.

Should it be desirable to use the modified construction shown in Figs. 5 and 6 then the offset locking projection 26 disposed at the outer end of the arm 25 will enter between two elements 12 at one side of the longitudinal center of the stringer instead of being wedged between the separated rows of elements 12 as in Fig. 4.

An important feature of the present invention above mentioned lies in the construction whereby the pull tab 29 cooperates with the locking arm 20 to move this arm to the unlocked position. This is accomplished in the construction shown by providing the tab 29 at its inner end with the inwardly projecting pintles 30 which enter the elongated slots 31 formed in the ribs 19, and the ends of these pintles after being introduced into the slots 31 are forced toward each other into abutting relation. This serves to slidably secure the pull tab 29 to the ribs 19 so that when this tab is pulled in one direction it will slide to one end of the slots 31 and when pulled in the opposite direction it will slide to the other end of these slots. This sliding movement is used to exert a camming action upon the locking arm 20 to force this arm to its unlocked position in which it is shown in dotted lines in Fig. 3. To this end the arm 20 of Figs. 1 to 4 inclusive and arm 25 of Figs. 5 and 6 is provided with the angularly disposed camming surfaces 32 and 33 one or the other of which is engaged by the pintle 30 when the pull tab is shifted from the position in which it is shown in Fig. 2 to one end or the other of the slots 31. These slots 31 preferably are curved upwardly at their ends lying towards the pivot pin 21 to thereby facilitate the action of the tab 29 in camming the locking arm 20 to its unlocked position as the slider 13 is moved by the tab 29 in the stringer closing direction.

It will be seen from the foregoing that by employing the construction of the present invention the pull tab 29 is slidably secured to an integral portion of the slider 13. This serves to provide a strong durable connection between the pull tab and its slider, and when the tab is advanced in

4

either direction along its anchoring slots from a central position it will exert a camming action upon the locking arm 20 to move this arm to the unlocked position.

Having thus described our invention, what we claim and desire to protect by Letters Patent is:

1. A locking slider for engaging and disengaging the elements of separable fasteners, comprising a body having top and bottom wings, a pair of spaced ribs integral with said top wing and extending substantially the length thereof, said ribs forming a channel therebetween which is open at its top, a locking arm pivoted on said body and positioned in said channel, a locking projection on said arm adapted to engage the fastener elements, resilient means acting upon said arm for urging said projection into engagement with said elements, a pull tab, said ribs having laterally aligned elongated slots therein which are encompassed by said ribs for retaining one end of said pull tab on said slider, said end of said pull tab being slidably and pivotally mounted in said slots and adapted to exert a camming action on said locking arm to disengage said locking projection from said elements and to actuate said slider.

2. A locking slider for engaging and disengaging the elements of separable fasteners, said slider comprising a body having top and bottom wings, a pair of spaced ribs integral with said top wing and extending substantially the length thereof, said ribs forming a channel therebetween which is open at its top, a locking arm pivoted on said body and positioned in said channel, a locking projection on said arm adapted to engage the fastener elements, resilient means acting upon said arm for urging said projection into engagement with said elements, a cam surface on said arm, a pull tab, said ribs having laterally aligned elongated slots therein which are encompassed by said ribs for retaining one end of said pull tab on said slider, said end of said pull tab being slidably and pivotally mounted in said slots for moving said slider and adapted to exert a camming action on said cam surface to disengage said projection from said elements when said slider is moved.

3. A locking slider for engaging and disengaging the elements of separable fasteners, comprising a body having top and bottom wings, a frog having an element separating end interposed between said wings, a pair of spaced ribs integral with said top wing and extending substantially the length thereof, said ribs forming a channel therebetween which is open at its top, a locking arm positioned in said channel and pivoted on said body, a locking projection on said arm adapted to extend downwardly in rear of said frog and engage the interlockable ends of the separated fastener elements, an actuating projection extending downwardly from said locking arm into a slot in the forward portion of said frog, resilient means in said slot acting upon said actuating projection for urging said locking projection into engagement with said elements, a V-shaped cam surface on said arm, said ribs having elongated slots therein, a pull tab having one of its ends slidably and pivotally mounted in said slots for moving said slider backward and forward over said elements and adapted to exert a camming action on said cam surface to disengage said projection from said elements when said slider is moved either backward or forward.

4. A locking slider for engaging and disengaging the elements of separable fasteners, compris-

ing a body having top and bottom wings, a frog connecting said wings, a pair of spaced ribs integral with said top wing and extending substantially the length thereof, said ribs forming a channel therebetween which is open at its top, a locking arm pivoted on said body and positioned in said channel, a locking projection on said arm extending through an opening in said top in rear of said frog and adapted to engage the separated ends of the fastener elements, resilient means acting upon said arm for urging said projection into engagement with said elements, a cam surface on said arm, said ribs having elongated slots therein, a pull tab having one of its ends slidably and pivotally mounted in said slots for moving said slider and adapted to exert a camming action on said cam surface to disengage said projection from said elements when said slider is moved.

5. A locking slider for engaging and disengaging the elements of separable fasteners on opposite tapes, said slider comprising a body having top and bottom wings, a frog connecting said wings, said top wing having an opening therein immediately in rear of said frog, a locking projection mounted on said body and extending through said opening and adapted to simultaneously engage at least two adjacent separated ends of said elements on opposite tapes, said projec-

tion having one element engaging side offset from the central vertical longitudinal plane of said slider and substantially parallel therewith and the other element engaging side converging rearwardly thereto, resilient means for urging said projection into engagement with said elements, and means for moving said slider backwards and forwards over said elements and simultaneously disengaging said projection from said elements when said slider is moved in either direction.
